UNITED STATES PATENT OFFICE

2,504,485

WRIST WATCH HOLDER FOR DISPLAY
CONTAINERSJack G. Allen, Libertyville, Ill., assignor to F. H.
Noble & Company, Chicago, Ill., a corporation
of Illinois

Application October 17, 1946, Serial No. 703,845

3 Claims. (Cl. 206—75)

1

This invention relates to display boxes and more particularly to a display box embodying a holder or frame of novel construction for mounting and retaining for display purposes a wrist watch equipped with leather straps or bands of other suitable material.

It was early recognized that buckling the leather straps of a wrist watch in a display box prior to its sale was undesirable because of the tendency of the straps to become set in a deformed or unnatural position and to become scarred or creased due to their tight frictional engagement with the buckle in passing therethrough. The straps were buckled in the display boxes in order to retain the watch in secured position and thus prevent their inadvertent detachment therefrom. To avoid the necessity of buckling the straps and their consequent disfigurement which detracted from their appearance, various types of display pads and holders have been devised and used commercially, but for one reason or another they neither proved satisfactory nor acceptable. Some holders were of such complicated construction that mounting of a wrist watch and its attached straps thereon and its removal therefrom were not readily accomplished, while others were deficient in their ability to retain the watch and straps against inadvertent detachment. Some holders also proved undesirable because a great percentage of the straps were concealed from view and thus defeated the prime purpose of the box and holder which was the display of the entire article offered for sale.

It is, therefore, an object of the present invention to provide an improved display box for wrist watches and other articles of jewelry.

Another object of the invention is to provide a wrist watch display box comprising a novel and improved type of holder or frame therefor and upon which a wrist watch and its attached straps may be readily and securely mounted and readily removed therefrom.

A further object of the invention is to provide a novel and improved type of holder or frame for a display box upon which a wrist watch or other article of jewelry, having attached straps, may be securely mounted without requiring the buckling together of the straps so as to cause permanent deformation or marring of the straps.

Still another object is to provide an improved type of holder or frame for a display box upon which a wrist watch, or other article of jewelry, having attached straps, may be mounted for display purposes without concealing any portions of

2

the watch or other article or any portions of the attached straps.

A still further object is to provide a wrist watch display box having an improved type of holder or frame comprising means for engaging and retaining the buckle of one wrist watch strap so that the straps may be pulled tight and the free end of the other strap passed over the buckle and through the keepers on the said one section of strap.

Other and further objects and advantages will become apparent as this description progresses, reference being had to the accompanying drawing, in which:

15 Figure 1 is a perspective view of one embodiment of the improved jewelry display box comprising the present invention showing a wrist watch and attached strap securely mounted in display position on the holder thereof; and

20 Fig. 2 is a top plan view of the same but with the wrist watch and attached strap drawn in broken lines for the sake of clarity.

The display box shown in the drawing comprises generally a body or base portion 10, a cover or lid 11 hinged to the base portion, and a holder or frame 12 mounted within the base portion. The base portion 10 has a continuous circular upstanding wall 13 comprising its front and side walls and also has a straight rear wall 14 where it is hinged to the cover 11. The cover 11 has a similar shape and outline and is adapted to rest upon and coincide with the walls of the base portion 10 when in closed position. Secured to the bottom wall 16 of the base portion 10 adjacent to the front wall is an arcuately shaped and raised support 17 having a front sloping portion 18 and a relatively flat top portion 19. The present invention, however, relates primarily to the article holder or frame 12, and therefore it is apparent that the base portion and the cover of the box may assume any shape or design.

The article holder or frame 12 is mounted at its front central section on the upper surface of the flat top portion 19 of the raised support 17 and extends rearwardly so as to occupy a substantially central position within the walls 13 and 14 of the box base 10. The holder 12 which is generally elliptical in shape and of a size substantially equivalent to that of a person's wrist, is formed from a curved vertically extending strip which is provided with an enlarged article-supporting face 20 at its front central portion and the free ends 21 and 22 of which terminate short of each other forming a gap therebetween. The end 22 of the holder 12 is bent or doubled back

upon the strip so as to provide a retaining lug or hook which serves as a means by which an article of jewelry such as a bracelet or a wrist watch may be securely mounted thereon for display purposes.

To demonstrate the operation of the display box and the article holder or frame 12 comprising the present invention, there is shown in the drawing a wrist watch 23 to which are attached straps 24 and 26 of conventional construction. The strap 24 has a buckle 27 secured to its free end and also a pair of keepers or loops 28 through which the free end of the strap 26 may be passed. To mount the watch 23 on the holder 12, the strap buckle 27 is first inserted through the gap 15 between the free ends of the holder 12 and over and in interengagement with the retaining lug or hook 22, after which the strap 24 is pulled around the outer vertical, curved surface of the holder 12 so that the watch 23 is properly positioned against the enlarged section 20 at the front of the holder. The strap 26 is then extended around the other curved side of the holder 12 and its free end is passed over or rearwardly of the buckle 27 and then through strap retaining members or keepers 28, thus by-passing the buckle 27 contrary to the ordinary manner of buckling the straps together.

The keepers 28 are of such restricted size, particularly when new and unworn, as to frictionally engage the free end of the strap 26 and thus serve to maintain the watch 23 and its attached straps 24 and 26 in tight frictional engagement with the outer vertical face of the holder 12. Because of the interengagement between the buckle 27 and the hooked lug 22 of the holder 12, no slippage results as the free end of the strap 26 is pulled tightly through the keepers 28. Thus, it is apparent that a wrist watch and its attached straps may be readily and securely mounted on the holder 12 with a minimum expenditure of time and effort, and that its disengagement and removal therefrom may be effected with equivalent ease in the event a prospective purchaser or wearer of the watch desires to try it on. When a watch is so mounted on the holder 12, the display box may be handled in the ordinary manner without causing the watch to become inadvertently loosened or disengaged therefrom.

It is to be noted further that since the strap 26 is not passed through the buckle 27 so as to become interengaged therewith in the normal, intended manner, but passes thereover and directly into and through the keepers 28, the strap is in no way deformed or marred by tight frictional engagement with the buckle or any other part of the holder 12. The straps of the watch may remain in the mounted and secured position above-described for a long period of time without becoming "set" in deformed position and without having permanent creases or scars made in the relatively soft polished surface of the leather by the buckle. Consequently, the straps 24 and 26, because of the novel manner of mounting on the holder 12 and because of the ease with which they may be engaged and disengaged with the holder, never become shopworn in appearance. Over a long period of frequent handling for demonstration to prospective purchasers, the straps retain their new, unmarred appearance and, consequently, no price concession need be made to compensate for the worn appearance.

Although there has been shown in the drawings and described in detail above one embodiment of the wrist watch holder for a display box comprising the present invention, it is to be understood that changes and modifications may be made in the details of construction without departing from the spirit and scope of the appended claims.

I claim:

1. In a display container for a wrist watch, and the like, equipped with straps, one of which is provided with a buckle, a wrist watch holder comprising a rounded, upstanding member having substantially vertical faces on its outer sides about which the straps may be extended for supporting the watch and straps in display position and a watch supporting area on one of said faces and being provided with a gap removed from said area and a hook-like retaining element projecting from said member at one side of said gap and adapted to be interengaged with said buckle of said one strap.
2. In a display container for a wrist watch, and the like, equipped with straps, one of which is provided with a buckle, a wrist watch holder comprising a relatively thin elongated strip formed into a rounded, upstanding member with its free ends spaced from each other defining a gap therebetween and having substantially vertical faces on its outer sides about which the straps may be extended for supporting the watch and straps in display position, a watch supporting area on one of said faces removed from said free ends, and a hook-like retaining element on one of said free ends projecting inwardly therefrom and adapted to be interengaged with the buckle of said one strap.
3. In a display container for a wrist watch, and the like, equipped with straps, one of which is provided with a buckle and a retaining element for said other strap, a wrist watch holder comprising a relatively thin elongated strip formed into a rounded, upstanding member with its free ends spaced from each other defining a gap therebetween and having substantially vertical faces on its outer sides about which the straps may be extended for supporting the watch and straps in display position, a watch supporting area on one of said faces removed from said free ends, and a hook-like retaining element on one of said free ends projecting inwardly therefrom and adapted to be interengaged with said buckle of said one strap, whereby the straps and watch may be pulled tightly around and supported on said holder and said other strap may by-pass said buckle and extend directly into engagement with said strap retaining member.
